[57] CLAIM

The ornamental design for a branching cable electrical connector, substantially as shown and described.

DESCRIPTION

FIG. 1 is a perspective view of the branching cable electrical connector showing my new design; FIG. 2 is a side elevational view thereof, the opposite side being a mirror image;

FIG. 3 is a top plan view thereof;

FIG. 4 is a bottom plan view thereof;

FIG. 5 is an end elevational view thereof;

FIG. 6 is an opposite end elevational view thereof. The cable is shown broken away in FIGS. 1-4 for ease of illustration only.

FIG. 3

FIG. 4

FIG. 5

FIG. 6
